UNITED STATES PATENT OFFICE.

HENRY J. WAIN, OF WHEELING, WEST VIRGINIA, ASSIGNOR TO WARWICK CHINA COMPANY, OF WHEELING, WEST VIRGINIA, A CORPORATION.

DESIGN FOR A PLATE OR SIMILAR ARTICLE.

Application filed May 14, 1925. Serial No. 13,438. Term of patent 7 years.

To all whom it may concern:

Be it known that I, HENRY J. WAIN, a citizen of the United States of America, residing at Wheeling, in the county of Ohio and State of West Virginia, have invented a new, original, and ornamental Design for Plate or Similar Article, of which the following is a specification, reference being had to the accompanying drawing, forming a part hereof.

The figure is a plan view of a dinner plate, showing my new design.

I claim:

The ornamental design for a plate or similar article as shown.

HENRY J. WAIN.
